UNITED STATES PATENT OFFICE.

JAMES HALL TAYLOR, OF OAK PARK, ILLINOIS.

CORRUGATING-MACHINE.

1,209,071.

Specification of Letters Patent. Patented Dec. 19, 1916.

Application filed April 23, 1915. Serial No. 23,381.

To all whom it may concern:

Be it known that I, JAMES HALL TAYLOR, a citizen of the United States, residing at Oak Park, in the county of Cook and State 5 of Illinois, have invented a certain new and useful Improvement in Corrugating-Machines, of which the following is a full, clear, concise, and exact description, reference being had to the accompanying drawings, forming a part of this specification.

The present invention relates to corrugating machines of the type for forming transverse corrugations in pipes, tubes and the like. Machines of this type are particularly useful in forming corrugated flues for 15 boilers of the internally fired type.

Heretofore it has been found very difficult to roll large and heavy tubes without causing surface abrasions. This difficulty 20 has arisen primarily in feeding the metal through the rolls due to the manner of driving of the rolls as practised in the present art.

One of the chief objects of my invention 25 is to provide an improved method and means for operating corrugating rolls or the like.

Another object is to provide improved means for adjusting the main rolls and the 30 guide rolls.

Another object of my invention is to provide means for adjusting the length of the corrugating rolls, and a still further object is to provide means for opening and closing 35 the rolls at different speeds.

When a heavy tube is to be rolled the stiffness of the metal demands a large driving friction between the driven rolls and the metal. This can only be secured by an increase of the pressure but increase in pressure on the roll tends to increase the depth 40 of the corrugations and consequently increases the difficulty of rolling. This causes the driven roll to slip and the surface of the tube is abraded and an unevenness in the 45 rolling of the tube is developed. In rolls of this type it is found advisable to make one of the rolls with rounded ridges and the other with fairly sharp ridges, and due to 50 increased surface of the round roll, it has been considered advisable to drive this roll, but the abrasions that are caused are highly undesirable. Attempts have been made to correct this by driving from the other roll, 55 but the driving surface is greatly reduced

and operation is unsatisfactory. I have solved the difficulty by applying a tractive effort on both surfaces of the tubes during rolling. The means which I employ automatically compensates for the differences in speed which are caused by the variations of inner and outer diameter at the points of rolling. This gives a marked improvement in the behavior of the feed and minimizes any tendency toward abrasion or 60 crooked rolling. I have provided a compensating connection to take care of the different speeds of the inner and outer roll and drive both rolls from a common source of power.

In order to enable those skilled in the art to practise the invention, I shall describe in the following specification with the aid of the accompanying drawings one embodiment in which my invention may appear.

Figure 1 is an elevation of one embodiment of my invention; Fig. 2 is a plan view of the same; Fig. 3 is a vertical longitudinal cross-section; Fig. 4 is an enlarged detail view of the slippage connection between the rolls; 80 Figs. 5 and 6 are details showing the manner of connecting the adjusting screws with the bearings; Fig. 7 is an end view, taken from the left of Fig. 1; Fig. 8 is a cross-sectional view taken on the line 8, 8, of Fig. 85 2; Fig. 9 is a transverse cross-section taken on the line 9, 9, of Fig. 2; Fig. 10 is an end elevation of the driving mechanism taken from the right of Fig. 1.

The corrugating machine comprises essentially the two co-operating rolls 1 and 2, which in the machine I have illustrated, are placed one above the other. These rolls are made up of sections built up upon shafts 3 and 4 in such manner that the width of the 90 corrugated portion may be varied at will. To this end the intermediate-bearing post 5 is laterally adjustable as viewed in Fig. 1, the sections 6 and 7 being removable in order to increase or decrease the width of the 95 corrugated portion of the rolls 1 and 2. The upper roll 1 is relatively fixed and the shaft 3, which supports it, has bearings relatively fixed in the yoke 8, the movable pillar 5 and the stationary pillars 9 and 10. Special 100 provision is made for the bearings 11 at the outer end of the roll in the yoke 8 as will be described later. The lower shaft 4 has adjustable bearings 12, 13, 14 and 15 mounted in the pillars 16, 5, 9 and 10, re- 110

spectively. The shaft 3 which bears the roll having the relatively sharp corrugations has a gear 17 keyed to the inner end thereof. This gear meshes with a pinion 18 mounted on the shaft 19 which has the gear 20 keyed upon the outer end thereof. The gear 20 meshes in turn with a pinion 21 secured to the clutch shaft 22. The clutch shaft 22 has the clutch elements 23 and 24 mounted thereupon, these clutch members being engageable with coöperating clutch members secured to the gears 25 and 26 respectively, as shown more clearly in Fig. 2. The gear 25 is driven by a pinion 27 mounted directly on the motor shaft 28 which may be driven by any convenient source of power as, for instance, an electric motor 29 as I have shown in Fig. 10. The gear 26 is driven in the reverse direction by means of a pinion 30 which is below the shaft 28 but geared thereto by means of the pinions 31 and 32 mounted upon the motor shaft 28 and the counter-shaft 33, respectively. The clutch members 23 and 24 are controlled by a hand lever 34 mounted upon an operating platform 35 and by throwing in the forward or reversing clutch, the corrugating rolls may be driven in the forward or reversing direction as desired, or may be disconnected from the driving motor. Thus by means of the gearing just described the upper roll 1 is driven by the motor.

I shall now describe the means whereby I am enabled to apply a tractive effort to both sides of the tube. A gear 36 is secured to the shaft 3 and below it on the shaft 4, but free to rotate thereon, is a similar gear 37. Gears 38 and 39, mounted on the counter-shafts 40 and 41, respectively, mesh with the gears 36 and 37 and with each other. It can thus be seen that as the shaft 3 is driven forward it will drive the gear 37. A flanged collar 42, (see Fig. 4) is keyed to the shaft 4 and rotates therewith. The flange on this collar is clamped between two flange members 43 and 44 which are normally held in contact with the flange on the collar 42 by means of the bolts 45 and springs 46. Suitable lining may be placed between the flanges 43, 42 and 44 in order to furnish the proper degree of friction. The flange 43 is keyed and bolted to the pinion 37 so that the same is compelled to rotate therewith when driven by rotation of the shaft 3. This provides a slippage connection between the shafts 3 and 4, such that there is always a tendency, determined by the amount of friction between the collar 42 and the flanges 43 and 44 for driving the shaft 4. The ratio of the gears 36 to 37 may be varied as desired.

The outer end bearing 11 of the upper roll 1 is provided with a suitable bearing box 11 held against upward movement by the yoke 8. The yoke 8 and the bearing box 11 are

suitably secured together by means of the pin 47 which serves as a key. The bearing box 11 is normally supported upon a rod 48 pivoted at 49 to the yoke 8. The yoke 8 is pivotally mounted upon the shaft 50 so that it can be swung out to clear the end of the roll in order to slip a tube or pipe over the roll 1 preparatory to rolling the same between the rolls 1 and 2. The rolls 1 and 2 are separated sufficiently at this time to allow of convenient placing of the tube upon the roll. Due to the length and weight of the roll on the shaft 3 the same sags down considerably and some means for restoring it to its normal position is necessary. When it is desired to replace the yoke 8, the rod 48 is swung under the bearing box 11 and then the yoke 8 is swung into position. As the yoke 8 is moved upward the rod 48 is thrust upward due to the toggle action between this rod and the short length of the yoke between the bearings 49 and the shaft 50. The pin 47 is thereafter inserted and the yoke remains in place to give the proper support to the shaft 3 when the rolls are pressed together during the operation of rolling a tube. The bearing boxes 12, 13, 14 and 15 for the lower shaft 4 are supported upon jack screws 51, 52, 53 and 54, respectively. These jack screws may be raised by means of a threaded worm wheel 55 each of which coöperates with a worm mounted on the shaft 56. The jack screws 51, 52 and 53 are connected to their respective bearings by means of the couplings shown in Figs. 5 and 6. The reduced end of the jack screws fits in a socket 57 and has a key 59 passing diametrically therethrough which key rests in a suitable slot 58 in the socket. This connection allows of ready separation of the parts even if the key 59 should become twisted or partially sheared. The jack screw 54 is connected by means of a tapered key 60 passing through a hole in the bearing box 15. Inasmuch as the weight of the shaft 4 and the roll 2 is upon the opposite end to that of the bearing 15 this bearing will need to support an upward pull and hence the same is keyed to the jack screw 54 as above indicated.

I have provided means for driving the raising and lowering mechanism at different speeds of operation in order that the roll 2 may be raised slowly during the operation of rolling or corrugating a tube and may be lowered quickly as when it is desired to insert or remove a tube from the rolls. To this end I have provided a gear 61 loosely mounted on a shaft 62 meshing with a pinion 63 secured to the motor shaft 28. The gear 61 may be connected with the shaft 62 by means of a suitable clutch 64 controlled by a hand lever 65. The shaft 62 is connected by means of suitable gears of different ratios, selectable by means of the clutch

66, to the countershaft 67. The shaft 67 may then be placed in driving relation of either forward or reverse direction with the shaft 56 by means of the clutch 68 and the 5 bevel pinions 69. The clutch 66 for changing speed and the clutch 68 for changing the direction of drive are controlled by hand levers 70 and 71, respectively.

As above explained, it may be found desirable to shift the bearing post 5 in order to increase or decrease the length of the rollers 1 and 2. This is especially desirable for rolling various lengths and thicknesses of tubes. When a short heavy tube is to be 15 rolled the bearings are brought closer together to prevent springing or bending of the rolls. To this end the shaft 56 is splined, as indicated in Fig. 3, in order to allow the worms, coöperating with the worm-wheel 55 20 of the jack screw 52, to be moved laterally without changing the height of the bearings 13. The bearing posts 16 and 19 are connected by suitable rods or stringers 72 and 73. I provide also a pair of guide rollers 25 74 and 75 on each side of the main rolls 1 and 2 for guiding the tubes which are to be corrugated and for supporting the same during the process of rolling. These rolls may be provided with rounded collars 76, as 30 shown in the drawings. The guide rolls 74 and 75 are mounted in suitable bearings 78 in the bearing posts 16 and 9, which bearings are provided with means for raising and lowering the same similar to the means 35 for lowering and raising the main roller 2. The jack screws 79 are secured to the bearings 78 by means of pins and sockets similar to those shown in Figs. 5 and 6, the jack screws 79 being lowered and raised by means 40 of suitable worm wheels 80 driven by worms 81 on the shafts 82. The yoke 8 which supports the outer end bearing 11 of the main shaft 3 may be suitably counterbalanced as by means of the weight 83 to lighten the 45 work of raising and lowering the same. This yoke is steadied against lateral motion by means of the guide 84. When the roller 2, which is mounted on the main shaft 4, is raised or lowered, the distance between centers of the shaft 41 and the main shaft 4 is 50 varied slightly.

The operation of the machine above described is obvious from the function of the parts set out. When it is desired to place a 55 tube or pipe in the machine for corrugating the same, the pin 47 is withdrawn from the yoke 48 and the yoke is swung outwardly. The guide rolls 74 and 75 are moved downward and the lower roll 2 is dropped a 60 sufficient amount to allow of ready insertion of the tube or pipe between the rolls. As soon as the same is in place the yoke 8 is swung back into place, the rod 48 lifting the roll to its proper position so that as the yoke 65 8 is brought up into position the bearing

will be cammed or toggled into position so that the same may be secured by the pin 47. The guide rolls 74 and 75 are then brought upward to bring the tube against the upper roll 1. The lower roll 2 is then raised to 70 bring suitable pressure upon the tube between the rolls. The operation of rolling is then carried on until the corrugations have been made of suitable depth, after which the guide rolls are lowered together with the 75 lower roller 2, the yoke 8 is swung outwardly and the corrugated tube removed.

I do not intend to be limited to the precise details of construction shown, as it is obvious that numerous modifications and 80 changes are possible without departing from the scope of my invention.

What I claim as new and desire to secure by Letters Patent is the following:

1. In combination, a pair of corrugating 85 rolls, common means for driving said rolls, and a compensating connection between one of said rolls and said driving means.
2. In combination, a pair of corrugating 90 rolls, common means for driving said rolls, a compensating connection between one of said rolls and said driving means, and means for varying the space between said rolls.
3. In combination, a pair of corrugating 95 rolls, a gearing between said rolls, a compensating connection in said gearing, and common means for driving both of said rolls.
4. In combination, a pair of corrugating 100 rolls, a driving connection between them, said driving connection including a compensating connection, and means to drive one of said rolls.
5. In combination, a pair of corrugating 105 rolls, a driving connection between said rolls, said driving connection including a compensating connection, driving means connected to one of said rolls, and means for varying the space between said rolls.
6. In combination, a pair of corrugating 110 rolls, one of said rolls having relatively sharp ridges, the other of said rolls having rounded ridges thereupon, means to drive the first roll, a driving connection between said second roll and said driving means, said connection comprising a compensating element.
7. In combination, a pair of corrugating 115 rolls, a shaft for each of said rolls, gears on said shafts, a pair of countershafts, gears 120 on said countershafts connecting with the other gears and with each other and a compensating connection between one of said gears and one of said shafts.
8. In combination, a pair of corrugating 125 rolls, each of said rolls comprising a shaft, gears on said shafts, a pair of countershafts, gears on each of said countershafts, said gears meshing with the other gears and with each other, a compensating connection be- 130

- tween one of said gears and one of said shafts and means for adjusting the space between said rolls.
9. In combination, a pair of corrugating 5 rolls, one of said rolls having relatively sharp ridges thereupon, each of said rolls comprising a shaft, gears mounted on said shafts, a pair of countershafts, gears on said countershafts, said gears meshing with 10 the other gears and with each other, a compensating connection between one of said gears and one of said shafts and driving means geared to said roll having relatively sharp ridges.
- 15 10. In combination, a pair of corrugating rolls, end-bearings for said rolls, intermediate bearings for said rolls, a removable support for one end bearing, cam means operated by replacing said support for raising 20 said end bearings.
11. In combination, a pair of corrugating rolls, arranged one above the other, end bearings and intermediate bearings for said rolls, a removable support for one end bearing, means for locking said support in place, 25 and means operable by restoring the support for raising the end bearing, said means comprising eccentric means.
12. In combination, a pair of corrugating 30 rolls, intermediate bearings and end bearings for said rolls, a yoke for supporting the outer end bearing of the upper roll, a shaft for said yoke, a rod connected to said yoke and mounted eccentrically of said shaft, said rod serving to raise said bearing into alignment with said yoke.
13. In combination, a pair of corrugating 35 rolls, intermediate bearings and end bearings for said rolls, a yoke for supporting the outer end bearing of the upper roll, a shaft, said yoke rotatably mounted on said shaft, a rod connected to said yoke and mounted eccentrically of said shaft, said rod serving to raise said bearing into alignment with 45 said yoke and means to lock said yoke to said bearing.
14. In combination, a pair of corrugating rolls, one of said rolls being mounted above the other, a removable bearing support for 50 the outer end of said upper roll, a positive drive for one of said rolls, a compensating drive for the other of said rolls and means for advancing one of said rolls toward or from the other.
- 55 15. In combination, a pair of corrugating rolls, one of said rolls being supported opposed to the other, means for freeing the outer end of one of said rolls, driving means connected to one of said rolls, gearing between said roll and said other roll, said gearing including a compensating connection, control means for advancing one of said rolls, and means for varying the speed of operation of said control means.
- 60 16. In combination, a pair of corrugating rolls, one of said rolls being arranged above the other, one of said rolls having sharp corrugations thereupon, end and intermediate bearings for each of said rolls, driving means connected to the roll having the sharp 70 corrugations, gearing connected between said rolls, said gearing including a compensating connection and means for lowering or raising simultaneously the end and intermediate bearings of said lower roll.
- 75 17. In combination, a pair of corrugating rolls, said rolls being arranged one above the other, end and intermediate bearings for said rolls, means for freeing the outer end of said upper roll, one of said rolls having relatively sharp projecting ridges between the outer and intermediate bearings, driving means for one of said rolls, gearing connected between said rolls, said gearing including a compensating connection and variable speed mechanism for simultaneously raising or lowering the outer and intermediate bearings of said lower roll.
- 80 18. In combination, a pair of shafts, corrugating rolls on said shafts, end and intermediate bearings for said shafts, said end bearings being relatively stationary, and said intermediate bearings being shiftable laterally with respect to said rolls.
- 85 19. In combination, a pair of shafts, corrugating rolls on said shafts, said rolls being adjustable in length, bearings on said shafts adjacent the ends of said rolls, one of said bearings on each roll being adjustable to accommodate adjustment of the length of 90 the rolls.
- 95 20. In combination, a pair of shafts, a plurality of rolling collars upon said shafts, idle collars on each shaft, bearing collars intermediate said rolling and said idle collars, and a shiftable bearing post for said bearing collars.
- 100 21. In combination, a pair of shafts, a plurality of roller collars upon said shafts, idle collars on each of said shafts, bearing collars intermediate said rollers and said idle collars, relatively-fixed end bearings for said shafts, and a shiftable bearing post for said bearing collars.
- 105 22. In combination, a pair of shafts, a plurality of roller collars upon said shafts, idle collars upon said shafts, bearing collars intermediate said roller and said idle collars, a shiftable bearing post for said bearing collars, and means to traverse one 110 of said rolls with respect to the other.
- 110 23. In combination, a pair of shafts, a plurality of roller collars upon said shafts, idle collars upon said shafts, bearing collars intermediate said roller and said idle collars and clamped therebetween, relatively-fixed end bearings for said shafts, a laterally-shiftable bearing post for said bearing collars, and means to traverse one of said rolls with respect to the other.
- 115 130

24. In combination, a pair of corrugating rolls, bearing pillars for said rolls, bearings for one of said rolls, said bearings being relatively stationary, bearings for the other roll, said bearings being movable in said pillars, jack screws connected to said bearings, said bearings having seats for said jack screws, open slots through said seats, and pins passing through said jack screws 10 and lying in said slots.
25. In combination, a pair of corrugating rolls, a bearing pillar for both of said rolls, a stationary bearing for one of said rolls, an adjustable bearing for the other of 15 said rolls, a jack screw coöperating with said adjustable bearing, said bearing having a seat for said jack screw, a slot through said seat, and a pin passing through said jack screw and lying in said slot.
26. In combination, a pair of corrugating rolls, relatively fixed end and intermediate bearings for one of said rolls, adjustable bearings for the other of said rolls, said adjustable bearings comprising end and 20 an intermediate bearing, jack screws for 25 said adjustable bearings, said bearings having seats for said jack screws, an open slot in one of said seats and a closed slot in another of said seats, pins passing through said jack screws and lying in said slots, and 30 means for operating said jack screws in unison.
27. In combination, a shaft, bearings for said shaft, jack-screws for said bearings, said bearings having seats for the ends of 35 said jack-screws, slots across said seats, pins in the ends of said jack-screws and lying in said slots, and common means for operating said jack-screws in unison.
28. In combination, a pair of corrugating rolls, a shaft for each of said rolls, gears on said shafts, a pair of countershafts, and gears on said countershafts connecting with the other gears and with each other. 40

In witness whereof, I hereunto subscribe 45 my name this 21st day of April, A. D. 1915.

JAMES HALL TAYLOR.
